UNITED STATES PATENT OFFICE

2,357,599

SANDBLASTING DEVICE

William P. Mott, Chicago, Ill., assignor to Joseph M. Schatz and Harry R. Glasser

Application October 31, 1942, Serial No. 464,031

6 Claims. (Cl. 51—13)

The invention relates to sand blasting devices wherein castings or other articles to be cleaned are arranged to be subjected to sand blasts from jets so that dust, scales, or impurities are removed to provide the articles with a clean surface.

It is an object of the invention to provide a device which is of inexpensive construction but highly efficient in operation.

A further object constitutes the provision of a device in which a plurality of jets are provided, one of said jets being mounted for reciprocation so that every part of an article is positively subjected to the action of a blast.

Another object constitutes the provision of a barrel or cage for receiving the articles to be treated which tumbler is maintained in floating relation and rotated by its supporting means.

A still further object constitutes the arrangement of parts and details of construction tending to enhance the utility and reliability of a device of the character described.

With these and other important objects in view which will appear from a perusal of the invention, the latter comprises the means described in the following specification, particularly set forth in the claims forming a part thereof, and illustrated in the accompanying drawings, in which

Fig. 1 is a side elevation of a device constructed in accordance with my invention.

Fig. 2 is a view from the line 2—2 of Fig. 1.

Fig. 3 is a section on the line 3—3 of Fig. 2.

Fig. 4 is a section on the line 4—4 of Fig. 3.

Fig. 5 is a perspective view of a cage for holding the articles.

Referring to the various views of the drawings the device includes a cabinet or casing generally designated by 10 having side walls 11, an end wall 12, a cover plate 13 and a door 14 hingedly secured to one side wall and provided with a window 15 to afford visual examination of the interior of the cabinet.

Shafts 16 and 17 and 18 in parallel relation and defining a triangle extend between the side walls 11. A belt 19 of rubber or other suitable material is trained around rollers 20 fast on said shafts 16, 17, and 18, the portion of the belt between shafts 16 and 18 being formed into a semi-circle to afford a seat for a cage generally designated by 21 in which the articles to be treated are received.

The cage comprises disks 22, which are connected by staves 23 and rings 24 hold the staves to the disks. The disks 22 are provided with a

large central opening 25 and in concentric arrangement thereto with a circular series of apertures 26 to afford egress for any sand or grit adhering to the disks 22 or rings 24.

In order to hold the cage 21 on the seat a roller 27 is secured to each side wall 11 and bears against the adjacent ring 24 to prevent the cage from leaving the arcuate portion of the belt 19.

The shafts 16, 17, and 18 project beyond the left side wall as viewed in Fig. 2 and are provided with a gear 28 around which a chain belt 29 is trained.

The shaft 18 also extends beyond the right side wall and has a gear 30 secured thereto.

15 A chain belt 31 is trained around the gear 30 and around a pinion 32 on the shaft of a reversible motor 33.

It is evident that the motor imparts drive to the shafts 16, 17, and 18 and consequently to the belt 19 which in turn causes rotation of the cage 21 maintained in floating position.

A motor driven suction fan 34 exhausts dusts and other impurities collecting in the cabinet.

Compressed air is supplied through a pipe 35 from which branch pipes 36, 37, and 38 provided with a valve 39 lead respectively to jets 40, 41, and 42.

Pipes 43, 44, and 45 lead respectively from the jets 40, 41, and 42 to the bottom of the cabinet where a supply of sand, grit, or other comminuted material is maintained.

Upon the compressed air escaping from the respective jets the sand is drawn into the jets by induction and sprayed onto the articles in the cage 21 as shown in Fig. 3. A partition 46 in the cabinet provides a bin for the storing of the sand.

The jet 41 is connected by a spring 47 to one side wall 11. To an arm 48 secured to the jet 41 is connected a cord 49 which is threaded through a bushing 50 on the right side wall 11 of the cabinet as viewed in Fig. 2.

A bracket 51 is secured on the outer side of the right side wall 11 which carries a pulley 52. 45 The cord 48 is wound around the pulley 52 and is secured to a pin 53 on the gear 30.

It is evident that upon rotation of the gear 30 the nozzle 41 is moved to and fro so that every portion of an article is effectively reached by the blast.

While the drawings show one embodiment of the invention numerous changes and alterations may be made without departing from the spirit of the invention.

I, therefore, wish to include all changes and

modifications, constituting departures within the scope of the invention as defined in the appended claims.

1. In a sand blasting device, a casing, a cage in said casing adapted to retain the articles to be treated, means for resiliently supporting said cage in floating position, and means for delivering a sand blast to said cage.

2. In a sand blasting device, a casing, a cage in said casing adapted to retain the articles to be treated, means for resiliently supporting said cage in floating position and rotating said cage, and means for delivering a sand blast to said cage.

3. In a sand blasting device, a casing, a cage in said casing adapted to retain the articles to be treated, a belt trained around rollers in said casing, said belt being slackened to afford a seat for said cage, means for imparting movement to said belt, and means for imparting sand blasts to said cage.

4. In a sand blasting device, a casing, a cage

in said casing adapted to retain the articles to be treated, a belt trained around rollers in said casing, said belt being arranged to support said cage, means for holding said cage to said belt, means for imparting movement to said belt, and means for imparting sand blasts to said cage.

5. In a sand blasting device, a casing, a cage in said casing adapted to retain the articles to be treated, means for floatingly supporting said cage and imparting rotation thereto, a nozzle discharging a sand blast onto said cage, and means for reciprocating said nozzle.

6. In a sand blasting device, a casing, a cage in said casing adapted to retain the articles to be treated, a belt trained around rollers in said casing, said belt being arranged to support said cage, means for imparting a drive to said belt, a nozzle discharging a sand blast onto said cage, and means controlled by said driving means for reciprocating said nozzle.

WILLIAM P. MOTT.
